UNITED STATES PATENT OFFICE.

CHESTER C. CHAPMAN, OF SOUTH BEND, INDIANA, ASSIGNEE TO NATIONAL WIRE BOUND BOX CO., OF SOUTH BEND, INDIANA, A CORPORATION OF INDIANA.

WOODWORKING-MACHINE.

No. 918,655.

Specification of Letters Patent. Patented April 20, 1909.

Application filed April 1, 1908. Serial No. 424,559.

To all whom it may concern:

Be it known that I, CHESTER C. CHAPMAN, a citizen of the United States, residing at South Bend, in the county of St. Joseph and State of Indiana, have invented certain new and useful Improvements in Woodworking-Machines, of which the following is a specification.

This invention relates to wood working machines.

One object of the invention is to provide an automatically operating table adapted to throw the material into and out of operative relation with the saw or other cutting mechanism.

A still further object of the invention resides in the provision of a feed table provided with means for automatically clamping the material upon the table for the operation of the latter into and out of co-operative relation with the cutting mechanism.

With the above and other objects in view, the invention consists in the combination and arrangement of parts hereinafter more fully described, illustrated in the accompanying drawings and particularly pointed out in the appended claims, it being understood that changes may be made in the form, proportion, size and minor details without departing from the spirit or sacrificing any of the advantages of the invention.

In the drawings:—Figure 1 is an end view of my invention. Fig. 2 is a top plan view. Fig. 3 is a front elevation. Fig. 4 is a detailed view of a strip of material mitered in accordance with my invention.

Referring now more particularly to the accompanying drawings, the reference character 1 indicates a suitable frame upon which is mounted in any suitable manner a rotatable shaft 2 to which the saws or other cutting mechanism may be secured, the saws in the present instance being arranged for a step mitering action upon the material, as indicated at 3. The shaft 2 is provided with a pulley wheel around which may work a driving belt 5 leading to any suitable driving mechanism not shown. Disposed over the cutting mechanism is a suitable fender 6, as shown.

Slidably mounted upon the frame 1 is a feed table 7 having brackets 8 and 9 secured thereto at one edge for the slideable reception of the shanks 9' of the respective clamps 10 and 11, there being helical or other springs 12

between the under face of each clamp 10 and 11 and the corresponding bracket designed to normally hold the clamp 10 out of operative relation with the material 13 upon the table 7, it being understood that more than the one strip of material shown may be placed upon the table for operation upon at one time. Each shank of these clamps 10 and 11 carries a small roller 14 adapted to bear against the under edge of the corresponding cam-bars 15 and 16, each, of the latter being reduced at its outer end to provide a shoulder 17. When the table 7 is in its inoperative position the rollers 14 of the shanks of the clamps lie upon one side of the shoulders 17 permitting the respective springs 12 to hold the clamps 10 and 11 out of operative position. However, when the table 7 is thrown to its operative position beneath the mitering elements 3 the rollers 14 of the shanks 9 of the clamps ride up and over the shoulders 17 of the cam-bars 15 and 16 causing the clamps 10 and 11 to be drawn downwardly toward the material upon the table against the action of the springs 12 and clamp the material firmly upon the latter. In view of the fact that certain strips of one material may be of greater thickness than the other material, the bars 15 and 16 are yieldably mounted upon the bolts 19 encircled by the springs 19', each bolt being mounted in a bracket 20 and having a head 21 between which latter and the bracket the springs 19' are disposed.

To reciprocate the feed table 7 backwardly and forwardly into and out of operative relation with the mitering elements 3, I provide the table 7 with depending lugs 22 to which is connected one end of a rod 23 having connection at 24 with the eccentric 25 mounted upon the drive shaft 26. To operate the shaft 26 and cause reciprocation of the table 7 by reason of the connecting element 23, the shaft 26 is provided with a pulley 27 fixedly secured upon the said shaft 26 and driven through the instrumentality of a suitable belt 28 having operative connection with any suitable driving means (not shown).

Mounted upon the shaft 26 is a positive clutch mechanism 29, which is thrown into and out of operation by the raising and lowering of a foot treadle 30 which is mounted upon a lever 31 pivoted at 32 to the frame. Pivotedly secured to the inner end of the lever 31 is a link connection 33 whose upper end is pivotally connected with the arm 34

which has direct connection with the clutch mechanism 29, as shown in dotted lines in Fig. 1 and in full lines in Fig. 2.

When the treadle 30 is not depressed the table 7 is not reciprocated, and to hold the treadle 30 normally in its upper position there is provided a suitable spring 35. When the treadle 30 is depressed against the action of the spring 35, the arm 34 is moved upon its pivot 34' and operates the clutch 29 to effect a connection of the pulley 27 to the shaft 26, whereby, upon operation of the belt 28, the table 7 with the material upon it, is reciprocated into and out of co-operative relation with the mitering elements, as clearly shown in dotted lines in Fig. 1, the reciprocation of the table 7 effecting an automatic clamping of the material upon the table, and it is obvious that when the material is cut or mitered at the point 36 in Fig. 2 that the clamp 10 will hold the cut strip or other material against accidental falling until removed by the operator of the machine.

From the foregoing it will be seen that I provide a positive feeding of the material into and out of operative relation with the mitering or other cutting elements and that I provide for an automatic clamping of the material as the table is reciprocated into and out of operative cutting position.

The length of the material to be cut may be determined by the operator and it is customary for the latter to feed the material over the table by hand.

35. What is claimed is:—

1. In a wood working machine, a frame having a pair of lugs projecting therefrom, each lug having an eye, a screw bolt passed through the eye of each lug, a feed table, means for reciprocating the feed table, a yieldably mounted clamp arranged to clamp the material upon the table, said clamp including a shank, a roller carried by the shank, and a cam-bar secured to said screw bolts and arranged for engagement by said roller to raise and lower said clamp alternately when the table is reciprocated.

2. In a wood working machine, a frame having lugs projecting therefrom, screw

bolts working through said lugs, a feed table, a cutting means, means for reciprocating the feed table toward and away from the cutting means, a pair of clamps yieldably mounted upon the table one upon each side of the line of cut of the cutting means, one clamp to hold the severed end of the material and the other clamp to hold the balance of the material whereby neither piece of material may accidentally move from the table after the cutting operation, each clamp including a shank, a roller carried by each shank, and a cam-bar coöperating with each clamp and provided with a shoulder on its underside for engagement by the roller of the corresponding clamp whereby the clamps may be raised and lowered upon the table when the latter is reciprocated.

3. In a wood working machine, a frame, a pair of brackets mounted upon the frame, each bracket having an opening, a feed table, a cutting means, means for reciprocating the feed table toward and away from the cutting means, a pair of clamps each including a head and a shank, the shank of each clamp being slidably mounted in the opening of one of said brackets, a spring secured to each bracket adjacent the opening in the latter and having engagement with the head of the corresponding clamp, the clamps being arranged whereby one clamp will hold the severed end of the material and the other clamp will hold the balance of the material to prevent accidental movement of the material from the table during the cutting operation, a roller secured to the shank of each clamp, and a pair of yieldably and adjustably mounted cam-bars arranged whereby each may be engaged by the roller of the corresponding clamp to effect a raising and a lowering of the clamps during the reciprocation of the table.

In testimony whereof I affix my signature; in presence of two witnesses,

CHESTER C. CHAPMAN.

Witnesses:
